UNITED STATES PATENT OFFICE.

JOHN HERBERT BOOTHE, OF INDIANOLA, IOWA, ASSIGNOR OF ONE-THIRD TO FRED CLARK AND ONE-THIRD TO ERNEST CLARK, OF INDIANOLA, IOWA.

NON-REFILLABLE BOTTLE.

1,167,791.

Specification of Letters Patent. Patented Jan. 11, 1916.

Application filed March 31, 1915. Serial No. 18,395.

To all whom it may concern:

Be it known that I, JOHN HERBERT BOOTHE, a citizen of the United States of America, residing at Indianola, in the county of Warren and State of Iowa, have invented certain new and useful Improvements in Non-Refillable Bottles, of which the following is a specification, reference being had therein to the accompanying drawing.

10 This invention relates to a non-refillable bottle and has for its principal object the production of a bottle from which the liquid contents may be easily and readily emptied which is provided with a valve for preventing the unauthorized refilling of the bottle.

Another object of this invention is the production of a pivoted valve which is so formed as to allow its pivot portions to be protected from the contents of the bottle, 20 whereby the pivot member will always work freely so as to open or close the passageway owing to the position in which the bottle is tilted.

Another object of this invention is the 25 production of a yieldable guide carried by the neck of the bottle at such a point so as to prevent unauthorized access to the valve member, and which will always act as a yieldable abutment for the valve for preventing the same from moving too far from the valve seat.

With these and other objects in view this invention consists of certain novel combinations, constructions, and arrangements of 35 parts as will be hereinafter fully described and claimed.

In the accompanying drawing:—Figure 1 is a central vertical section through the assembled device. Fig. 2 is a fragmentary 40 vertical section through the upper portion of the bottle of the neck showing the valve member in an open position. Fig. 3 is a section taken on line 3—3, of Fig. 1. Fig. 4 is a section taken on line 4—4, of Fig. 1. Fig. 5 is a detail perspective view of the 45 pivoted valve. Fig. 6 is a transverse sectional view through the valve. Fig. 7 is a fragmentary perspective view of a portion of the bottle neck showing the pocket formed 50 therein.

Referring to the accompanying drawing by numerals 1 designates the body of the bottle upon which the neck 2 is blown. This bottle is adapted to be filled through the 55 bottom 3, at which time the central portion

4 thereof is adapted to be blown so as to form a solid bottom. The neck 2 preferably converges toward its upper end and has formed adjacent its lower end an annular groove 5 which is adapted to carry the 60 wire guard 6. This guard 6 is clearly shown in Fig. 4, wherein it is greatly enlarged for the purpose of disclosing the specific construction thereof. This guard has its outer periphery or ends of the wire fitting in the 65 groove 5, thereby preventing the passing of a foreign instrument beyond the same, and, therefore, unauthorized access to the valve is prevented.

The valve member comprises a cap-like 70 body 7 having an even lower face 8. The body is preferably formed of a glass portion of similar material and has extending therefrom an integral shank 9 terminating in the bearing portion 10 in which there is 75 formed a transverse opening 11. The neck 2 has a rounded pocket 12 formed therein, and this pocket 12 is provided with the straight side walls 13. This pocket is adapted to receive the round bearing end 10 80 which fits snugly therein as clearly shown in Fig. 3. The neck 2 is also provided with a transverse bore 14 which registers with the opening 11 formed in the bearing 10 when the valve member is in position. The pin 85 15 may then be passed through the bore 14 and the opening 11, thereby pivotally retaining the valve in position.

By referring particularly to Figs. 3 and 7 it will be seen that the pivot portions of 90 the valve will be formed so as to be positioned within the pocket 12, and therefore, the liquid contents of the bottle will be prevented from coming into contact therewith or from having free access to the pivot portion, and thus the pivot portion will be prevented from corroding or otherwise becoming less efficient in operation, and prevent the valve member from freely swinging to a closed position. A rubber gasket or 95 a gasket of some suitable material as shown at 16 is secured to the body 7 of the valve upon its lower surface 8, and this gasket 16 is adapted to rest upon the shoulder 17 which constitutes the valve seat when the 100 bottle is in a vertical position. By referring to Fig. 1 it will be seen that the body 1 has its open end being reduced to form the shoulder 17, and it is upon this shoulder 105 that the neck 2 is blown.

The yieldable wire guard 6 is first positioned in the groove 5 at which time the pivoted valve member may also be placed in engagement with the neck and the pin 15 5 passed through the bore 14 and opening 11. The neck 2 may then be blown upon the upper portion of the body 1. The bottle may then be filled at which time the central portion 4 may be blown so as to form a solid 10 bottom 3. As it is desired to empty the liquid contents from the body 1, the bottle may be tilted as shown in Fig. 2. The valve body 7 will then swing into engagement with the yieldable guard 6 which will give 15 slightly as indicated in dotted lines in Fig. 2, and in this manner any danger of the valve member becoming chipped or broken, as well as the portions adjacent the groove 5 will be prevented owing to the resiliency 20 of the guard 6. It will be seen that this guard will only allow the valve to swing for a spaced distance from the shoulder 17. As soon as the bottle is turned to its normal 25 vertical position, the valve member will again swing to its normal position so as to allow the gasket 16 to rest upon the shoulder 17, thereby preventing any foreign contents being forced into the bottle. As above 30 stated, the bearing portion 10 of the valve 7 fits snugly within the pocket 13, and, therefore, will ride evenly thereon as the valve pivots. Furthermore, since the pin 15 passes through the opening 11 of the bearing 10, the valve will be allowed to 35 swing freely while the pivot portions will be prevented from becoming inoperative owing to the accumulation of foreign substance therearound.

From the foregoing description it will be 40 seen that a simple and efficient valve-non-refillable bottle has been produced which

will allow the liquid contents of the bottle to be easily emptied therefrom, and which is so formed as to prevent foreign contents to be forced into the bottle owing to the 45 fact that the pressure will cause the valve member to become firmly seated upon the valve seat.

Having thus described the invention what is claimed as new, is:—

In a non-refillable bottle, the combination of a body having a neck formed thereon, said body provided with an annular shoulder forming a valve seat, said neck provided with a rounded pocket having vertical side walls, a valve member carried by said neck, said valve member comprising a body having an integral shank extending therefrom and terminating in a bearing portion, said bearing portion provided with a transverse opening, said bearing portion fitting snugly within said pocket, a pin passing through said neck through the opening in said bearing portion for pivotally retaining said valve member in its correct 65 position, said pocket being adapted to retain said valve member against wobbling and at the same time allow the same to pivot freely, said bearing portion and said pin being protected by said pocket, whereby the liquid 70 contents of said body will be prevented from engaging said pin and bearing, thereby corroding the same and preventing the valve member from operating efficiently, and a guard carried by said neck for preventing 75 unauthorized access to said valve member.

In testimony whereof I hereunto affix my signature in presence of two witnesses.

JOHN HERBERT BOOTHE
